UNITED STATES PATENT OFFICE

MARK DEAN, OF NEWARK, NEW JERSEY; FAY WALTER DEAN EXECUTOR OF SAID MARK DEAN, DECEASED

ELECTROFLUID VALVE

Application filed January 28, 1929. Serial No. 335,438.

This invention relates to that class of valves in which the openings and closing of the valve admits, or keeps out, as occasion requires, the supply of power for driving a suitable motor and commonly known as "control valves." More particularly the invention relates to such valves where the power admitted is of a liquid or gaseous nature and, therefore, known as "motive fluid."

Among the many important uses to which such control valves are put, may be mentioned the regulation of the draft of, and hence the heat received by or given off from, a boiler, furnace, or the like, at any allotted time, or for any allotted work. For this purpose, the motor driven by the motive fluid is frequently a diaphragm, or the like, so arranged as to communicate the desired motion, usually slight, to a lever, or other device, which controls the draft in question.

The object of my invention is to provide a simpler, more efficient, more sensitive, more reliable, and less expensive type of this class of valves.

The, at present, preferred embodiment of my invention is shown in the accompanying drawings in which:—

Figure 1 is a front elevation.

Figure 2 is a bottom plan.

Figure 3 is a top plan.

Figure 4 is a vertical section on line 4—4 of Fig. 3.

Figure 5 is a vertical section on line 5—5 of Fig. 3.

Figure 6 is an enlarged detail of the inlet end of the valve.

Figure 7 is a section on line 7—7 of Figure 6.

Figure 8 is a section on line 8—8 of Figure 6.

Same letters indicate similar parts in the different figures.

A, is a base-board, or bracket, on which the valve-casing B, is mounted in any suitable manner, as by screws *a*, *a*. C, is the valve-rod, or bar, of suitable construction and, preferably, of metal. The valve-casing, as best shown in Figures 5, and 6, is a casting, tubular at its two ends *b*, *c*, and squared at the center, to form a hollow chamber *e*,

with a removable cover, or lid, *f*, held by screws *g*, *g*. By removal of this lid, free access may be had to the interior of the casing for the purposes of assembling the parts of the valve,—oiling, cleaning, adjusting and the like.

The tubular ends of the casing have external screw-threads *h*, *h*, to receive internally screw-threaded caps, or couplings, D, D, by which the inlet and outlet plugs, E, F, are drawn into watertight connection with the valve casing. These plugs are threaded, respectively, on the inlet and outlet pipes, G, H, and are each provided with an annular flange, *i*, *i*, to be gripped by the plug, and a tapering nozzle, *j*, *j*, which nozzles are alternately opened and closed by the shifting of the valve-rod, as hereafter explained, with the effect that, when the inlet nozzle is open the outlet, or discharge nozzle is closed, and vice versa. It is to be understood that at all times when the valve is in condition for action, the interior of the valve-casing, and its branches, are filled with the motive-fluid received through the inlet nozzle, and that this motive fluid exerts its motive pressure when the inlet nozzle is open and relaxes that pressure when the outlet nozzle is opened, and the inlet closed.

The construction and mechanism of the valve, by which the alternate actions of the motive fluid are produced and utilized, in a simpler more effective, more sensitive, more reliable, and less expensive construction than has been hitherto possible will now be explained.

The valve-rod C, is slidably supported within the casing B upon a thrust-sleeve, I, of suitable diameter for easy slipping in the interior of the tubular ends of the casing B. The shift to and fro, that is from contact with the inlet nozzle to contact with the outlet nozzle, is very slight, and is brought about by the oppositely extending rocker-arms, *k*, *k'*, mounted on the shaft 1, in such relation that when one of the arms as *k'*, approaches the horizontal position shown in Figure 5, the rotation of the disc *m'*, on the peg at the outer end of the arm, by a cam-like action pushes the valve-rod toward the inlet nozzle, and

closes the inlet as shown,—while the other arm communicates a reverse cam-like action to its disc *m*, thus permitting the withdrawal of the outlet end of the valve rod from contact with the exhaust nozzle. And vice versa, when the valve rod is shifted to open the inlet and close the outlet. To insure the desired sensitiveness, quickness and effectiveness of these shifting operations, the valve rod is provided with two sets of coiled springs, *n*, *n'*, at each end. The inner coiled spring, *o*, is a compensating spring designed to correct any tendency which may exist by reason of the rolling contact of the disk on the end of the rocker arm when acting as a cam, to make perfect connection at the nozzle mouth, this spring should be at least twice as strong as the outer spring, *n'*, the function of which is to act as a sort of buffer and assist in throwing back the end of the rod when the nozzle to which it is applied is opened. This spring may be identified as a buffer spring, as a distinction from the compensating spring. It would be obvious that the pressure of the motive fluid within the valve casing is always active, being approximately two atmospheres, or more. This pressure, therefore, is always exerted against the opening of either the inlet or outlet nozzle, and in both cases the pressure of the compensating spring is necessary. The buffer spring at the inlet opening may, if desired, be dispensed with as the pressure of the motive liquid, or fluid, from the outside of the valve has been found sufficient to open the inlet without such buffer. At the outlet end, however, the buffer spring has been found useful.

The impulse by which this shifting of the rocker-arms is brought about, may be electric or otherwise, but, as electricity, is preferable, electric mechanism is shown in the drawings for that purpose.

A double-acting solenoid magnet *J*, with its two spools of wire, *K*, *K'*, is mounted in suitable proximity to the valve-casing *B*. Each spool is wound on a hollow spindle *L*, *L'*, which is screw-threaded at its upper end into the valve-casing at *p*, *p'*, and is closed at its lower end by a plug *M*, *M'*. Within each hollow spindle is an armature *N*, *N'*, slidably hung therein from one of the rocker-arms *k*, *k'*, as shown in Figure 5. Three contact posts are mounted upon the top of the bracket *A*, marked plus and minus,—the minus connection being *q*, and the positive, *r*, *r'*. A suitable switch *T*, is mounted near the posts, *q*, *r*, *r'*, and is operated by a switch-plate *U*, mounted on a lever *O*.

The lever *O*, is pivoted on the bracket *A*, at *t*, and is connected at one end by a wire, or chain, *s*, to a damper, or other mechanism to be controlled. (Not shown). The lever is raised and lowered by a bellows, (see Figure 4) or diaphragm, or other type of convenient

motor, *P*, which is mounted on, or conveniently near, the bracket *A*, and operated by the pressure of the motive fluid in the valve-casing *B*. The stem *Q*, rises from the top of the bellows and is pivoted to the lever *O*, at *u*, and as the stem rises it pushes up the lever, thus, causing the lever to shift the switch *T*. The motive fluid is admitted to the bellows by the U-shaped connection pipe *S*, leading thereto from the bottom of the valve-casing, as shown in Figures 1, 2, 4, and 5.

The many advantages of my improved electro-fluid valve, I think, will be obvious to those familiar with the art, without further explanation.

I claim:—

An electro-fluid valve provided with a slideable valve-rod adapted to ply between the inlet and outlet openings of said valve, and a pair of rocker-arms located in the hollow chamber of said casing, adapted to impart reciprocation-movements to said rod,—said rod being provided with two sets of coiled springs at each end, the inner spring being approximately twice as strong as the outer spring and adapted to serve as a compensating spring for the buffer action of the outer spring.

MARK DEAN.
